UNITED STATES PATENT OFFICE.

WILLIAM GEORGE WEBB, OF BALTIMORE, MARYLAND, ASSIGNOR TO THE CHRISTOPHER LIPPS COMPANY, OF MARYLAND.

DESIGN FOR A CAKE OR BAR OF SOAP.

SPECIFICATION forming part of Design No. 27,556, dated August 24, 1897.

Application filed May 12, 1897. Serial No. 636,241. Term of patent 14 years.

To all whom it may concern:

Be it known that I, WILLIAM GEORGE WEBB, a citizen of the United States, residing at Baltimore, in the State of Maryland, have invented and produced a new and original Design for a Cake or Bar of Soap; and I do hereby declare the following to be a full, clear, and exact description of the same, reference being had to the accompanying drawings, forming part hereof, and in which—

Figure 1 is a plan view of a bar or cake of soap, showing my design; and Fig. 2 is a sectional view taken on the line $x-x$ of Fig. 1.

My design consists of a cake or bar of soap B, which I form oblong in shape and with curved ends, and the flattened broad surface of which I ornament with a series of knobs or knots A, so that the oblong face of the cake will present the appearance of a number of mounds or knolls with intervening plane surfaces,

said mounds and intervening planes being made the prominent or leading features of the design. In the middle of the face of the cake is formed an oblong plane surface C, around which the knots or knobs form a border and which is designed to receive the name which may be used to designate the cake or bar.

Having described my invention, what I claim as new, and desire to secure by Letters Patent, is—

The design for a bar or cake of soap, as herein shown and described.

In testimony whereof I affix my signature in presence of two witnesses.

WILLIAM GEORGE WEBB.

Witnesses:
